Form 4-1982, p. 19, Scooter.

Primary Examiner—Charles A. Rademaker
Attorney, Agent, or Firm—Staas & Halsey

[57] **CLAIM**

The ornamental design for a scooter, substantially as shown and described.

DESCRIPTION

FIG. 1 is a front perspective view of a scooter showing my new design;

FIG. 2 is a top perspective view thereof; and

FIG. 3 is a side perspective view thereof, the side opposite being substantially a mirror image.

The unshown bottom of the design is substantially plain and unornamented.

FIG. 2.

FIG. 1.

FIG. 3.
